Primary Examiner—Prabhakar Deshmukh(74) *Attorney, Agent, or Firm*—Christie, Parker & Hale, LLP(57) **CLAIM**

The ornamental design for a releasable attachment apparatus, as shown and described.

DESCRIPTION

FIG. 1 is a perspective view of a releasable attachment apparatus showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

The broken lines, which define the bounds of the claimed design, form no part thereof.
